Inventor

UNITED STATES PATENT OFFICE.

CHARLES G. WALL, OF BROOKLYN, NEW YORK.

CALENDAR PAD.

Application filed August 12, 1927. Serial No. 212,588.

My present invention relates to improvements in calendar pads involving the use of temporary binders for loose leaves. The device of my invention is adapted for use in various ways as, for instance, a wall calendar when it is suspended in vertical position convenient for use, or the device may be used as a desk calendar and memoranda pad, when it lies in horizontal position. By the utilization of the device of my invention, a calendar pad of loose leaves and a memoranda or scratch pad of loose leaves are provided in compact form and in position for ready access, and such a device may for instance be used upon the desk of a doctor for reference to the dates, and for having a handy prescription pad or memoranda pad in convenient position for use.

The calendar pad involves the use of two temporary binders and loose leaf pads, together with movable covers for the pads, which covers are preferably transparent. Means are provided on the base members that support the pads for coaction with the cover members, whereby the cover performs the function of a paper weight and retains the loose leaves of the pad against displacement as the thickness of the pad decreases and as the cover recedes toward the base member of the pad.

The invention consists in certain novel combinations and arrangements of parts covering both forms of temporary binder, and in details of construction in the parts as will be hereinafter more fully described and claimed.

In the accompanying drawings, I have illustrated one complete example of the physical embodiment of my invention where in the parts are combined and arranged according to the best mode I have so far devised for the practical application of the principles of my invention.

Figure 1 is a face view of a calendar pad, which may be either a wall device or a desk device;

Fig. 2 is an edge view of the calendar showing it in vertical position as when suspended from a wall;

Fig. 3 is an edge view with the leaves of the pads omitted, and the pads indicated by dotted lines, with parts broken away for convenience of illustration;

Fig. 4 is a transverse sectional view of the device at line 4—4 of Fig. 3; 55

Fig. 5 is a plan view showing the recessed supporting base and the tiltable base member supported therein; and

Fig. 6 is a detail sectional view showing the relation between the hinged cover plate 60 and the tiltable base member to compensate for decreased thickness in the memoranda pad.

In carrying out my invention, whether a wall device or a desk device is used, I employ a rectangular base board 1 which may be fashioned from any suitable material, and with this base board I utilize a spaced intermediate board 2 parallel with the base board and supported therefrom in any desired manner by transverse partitions 3 and 4. 65

The loose leaves of the calendar are indicated by the numeral 5 in Fig. 2, and the calendar pad is indicated by dotted lines in 75 Figs. 3 and 4.

The loose leaves forming the calendar pad are provided with spaced perforations so that they may be slipped over the two spaced hollow posts 6. Each of these posts has internal threads to receive a retaining screw 7 that is passed through an opening in the intermediate board 2 and screwed into the tubular or hollow post 6. The free end of the tubular post is provided with a threaded 80 stud or bolt end 8, and a nut 9 is threaded on this stud end. The cover plate for the calendar pad is preferably a glass panel as 10, preferably of beveled plate glass, and of sufficient thickness to form a paper weight 90 for the loose leaves of the calendar pad. This cover is hinged at 11 to a hinge plate 12 that is secured on the head or cross bar 10^a, and this cross bar and the plate 12 are provided with holes as 13 to accommodate the 95 posts 6. The plate 12 may be of brass or other metal that may be polished for ornamental purposes, and the nuts 9 may also be of ornamental metal and may be made in any desired shape. It will be apparent that as 100 the weekly calendar leaves are torn from the posts 6, that the thickness of the calendar pad will be decreased, and the glass cover plate 10 with its cross bar 10^a will recede toward the intermediate base board 2. The 105 holes 13 are of sufficient size to permit this

movement of the cover plate 2 and its cross bar 10^a with relation to the posts.

A pair of spring arms 14 which are attached at 15 to the base board 1 project in such relation to the calendar pad and the cross bar 10^a as to frictionally engage the end of base board 2. These two spring arms 14 are used as card receivers, as it will be apparent that a card or cards may be slipped 10 in between the spring arms 14 and the bar 10^a or the calendar pad and such card or cards will be frictionally retained in position.

Between the base board 1 and the intermediate board 2 and the partitions 3 and 4 a pocket 16 is provided in which may be placed or stored appropriate articles, such as a telephone directory book.

In connection with the base board 1, I also 20 employ a scratch pad or memoranda pad 17 also made up of loose leaves. This pad, like the calendar pad 5, is retained between a base member and a hinged cover plate also preferably made up of plate glass, and beveled. The glass panel is secured to a hinge plate 19, and this hinge plate is hinged at 20 to hinge members on the intermediate board 2. It will be apparent that as the leaves of the scratch pad are used and with- 25 drawn from beneath the cover plate 18, that the latter will swing on its hinges, as indicated in Fig. 6. To compensate for this swinging movement of the cover plate 18, I provide a movable or tiltable base member 21, 30 which is located in a recess 22 provided therefor in the base member 1. This tiltable base is provided at opposite sides with trunnions or pins 23 which are carried in the base member 1, and these pins permit the inner 35 edge of the tiltable base member to swing as indicated in Fig. 6, to bring the tiltable base member 21 and the hinged cover plate 18 into approximate parallelism. The free end of the tiltable base member 21 is supported 40 by a T-shaped spring plate 24 which has one end secured as at 25 to the base 1. This spring plate may be of any desired shape, and is designed to support the tiltable base 21, and to swing it on its hinge or pivot, to 45 compensate for decreased thickness of the pad 17. Thus as the thickness of the pad is decreased, the cover plate 18 recedes, and the tiltable supporting base 21 is swung by the spring plate 24 to compensate for the 50 movement of the cover plate, and to retain the remaining loose leaves of the pad in compact form. The under face of the free edge of the tiltable supporting base may be grooved as at 26 to accommodate the plate 24, and the partition 4 may be slotted as at 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 3. The combination in a temporary binder with a recessed base member and a base pivoted in the recess for tilting and having a depression near its free-end edge, of a cover plate and means for hingedly mounting said cover at a predetermined distance above said recessed base member, and means for pressing the end of the tiltable base against the under surface of the members of the hinge, whereby loose leaves are retained between the undersurface of the members of the hinge and the depression in the tiltable base. 10
- 5 In testimony whereof I have affixed my signature.

CHARLES G. WALL.
